(57) CLAIM

I claim the ornamental design for a base for cart for exhibiting audio/visual devices or the like, as shown and described.

DESCRIPTION

FIG. 1 is a top perspective view of a base for cart for exhibiting audio/visual devices or the like;

FIG. 2 is a front elevational view of the claimed design of FIG. 1;

FIG. 3 is a rear elevational view of the claimed design of FIG. 1;

FIG. 4 is a right side elevational view of the claimed design of FIG. 1;

FIG. 5 is a left side elevational view of the claimed design of FIG. 1;

FIG. 6 is a top plan view of the claimed design of FIG. 1; and,

FIG. 7 is a bottom plan view of the claimed design of FIG. 1. The broken lines in the drawings are for illustrative purposes only and form no part of the claimed design.
